UNITED STATES PATENT OFFICE

105,186

DESIGN FOR AN END STANDARD FOR THEATER CHAIRS

Austin C. Sellers, Menominee, Mich., assignor to
Heywood-Wakefield Company, Gardner, Mass.,
a corporation of Massachusetts

Application May 24, 1937, Serial No. 69,515

Term of patent 7 years

To all whom it may concern:

Be it known that I, Austin C. Sellers, a citizen
of the United States and a resident of Menominee,
county of Menominee, and State of Michigan,
have invented a new, original, and ornamental
Design for an End Standard for Theater Chairs,
of which the following is a specification, reference
being had to the accompanying drawing forming
a part thereof, in which Fig. 1 is a perspective view

of an end standard for theater chairs, showing
my new design and Fig. 2 is a detail sectional
view through a part of the standard as taken on
the line 2—2 of Fig. 1.

I claim—

The ornamental design for an end standard
for theater chairs substantially as shown.

AUSTIN C. SELLERS.
